Primary Examiner — Elizabeth J Oswecki

(74) Attorney, Agent, or Firm — Lerner, David, Littenberg, Krumholz & Mentlik, LLP

(57) **CLAIM**

The ornamental design for a spindle key, as shown and described.

DESCRIPTION

FIG. 1 is a top perspective view of a spindle key showing our new design;

FIG. 2 is a left side view thereof, the right side view being a mirror image thereof;

FIG. 3 is a front view thereof;

FIG. 4 is a rear view thereof; and,

FIG. 5 is a top plan view thereof, the bottom plan view thereof.

The broken lines shown in the drawings represent portions of the spindle key that form no part of the claimed design.

1 Claim, 2 Drawing Sheets
